UNITED STATES PATENT OFFICE.

HENRY J. MESCHER, OF DAYTON, OHIO.

RADIATOR CAP.

Application filed April 6, 1926. Serial No. 100,160.

This invention relates to radiator caps and one object of the invention is to provide such a cap which can be easily applied to the filling pipe of a radiator of an automobile 5 or the like but which cannot be readily removed therefrom.

To this end it is a further object of the invention to provide a radiator cap comprising two parts rotatably connected one to 10 the other and to interpose between these parts a pawl and ratchet connection of a very simple but highly efficient type which will cause the two parts to be rotated together in one direction but will permit one 15 of the parts to rotate in a reverse direction independently of the first mentioned part.

A further object of the invention is to provide such a radiator cap with a gravity operated floating pawl of a very simple inexpensive type which will be positive in its 20 operation.

Other objects of the invention will appear as the device is described in detail.

In the accompanying drawings Fig. 1 is a 25 plan view, partly broken away, of a radiator cap embodying my invention; Fig. 2 is a front elevation, partly broken away, of such a cap; Fig. 3 is a side elevation of such a cap partially broken away to show the 30 pawl and ratchet connection; Fig. 4 is a plan view of that portion of the cap which is connected with the radiator; and Fig. 5 is a plan view of the collar.

In these drawings I have illustrated one 35 embodiment of my invention and have shown the radiator cap as comprising three parts, to wit; an inner or connecting part 1, a rotatable part of collar 2 mounted on the part 1 and a closure 3. The inner part 1 is 40 tubular in form and is provided, in the present instance, with internal screw threads by means of which it may be screwed onto the filling pipe of the radiator. The upper portion of this tubular member has in its 45 outer wall a circumferential channel 4, the lower wall 5 of which constitutes a shoulder and has formed therein a tapered recess 6, the forward wall of which constitutes in effect a ratchet tooth.

50 The collar 2 extends about the upper portion of the tubular member 1 and has a circumferential rib 7 which extends into the channel 4 of the tubular member and serves to permanently but rotatably connect the 55 collar with the tubular member. The two parts may be assembled in any suitable

manner, as by swedging the upper flange of the channel 4 into a position above the rib 7. The collar 2 is provided with a recess overlying the shoulder 5 and this recess is preferably in the form of a slot 8 formed in the rib 7 and arranged at a slight angle to the vertical. Loosely confined within the slot 8 of the rib 7 is a floating pawl 9, the lower edge of which rests upon the shoulder 5. This pawl is freely movable within the recess 8 and as the collar is rotated on the tubular member the pawl will ride over the upper surface of the shoulder 5 until it is brought into line with the recess 6 and it will then drop into that recess by gravity. When the pawl has entered the recess in the shoulder the forward end of the pawl will engage the forward wall of the recess 6 in the shoulder and the rear end of the pawl will be engaged by the rear wall of the recess 8 in the collar, thus causing the tubular member to be rotated with the collar. If the collar is rotated in a reverse direction the pawl will ride out of the recess and move freely over the shoulder, thus permitting the free rotation of the collar in a reverse direction with relation to the tubular member. The slightly inclined position of the slot permits of the free movement of the pawl therein and provides a firm contact between the end thereof and the wall of the recess. In the present instance, the collar is provided with laterally extending bars 10 which are convenient but not necessary for 90 the rotation of the collar.

The closure 3 is carried by the collar and, as here shown, has rearwardly extending pivot lugs 11 which embrace a pivot lug 12 rigidly secured to the collar and are connected therewith by means of a pivot pin 13. The closure 3 also has, at its forward edge, pivot lugs 13, between which is pivotally mounted a latch 15 which is movable into and out of a position between two lugs 16 rigidly secured to the collar and having their lower edges slightly recessed. The latch bar has laterally extending pins or lugs 17 arranged to engage beneath the lugs 16 and retain the latch in locking position. Preferably the pins 17 are arranged out of line with the axis of the latch so as to have a cam action on the recessed lower edge thereof to firmly retain the closure in its closed position.

110 The operation of the device will be readily understood and it will be apparent that when

the cap is to be attached to the radiator the collar is rotated in a forward direction, thus causing the tubular connecting member to be rotated therewith and permitting the same to be screwed onto the filling pipe. When the collar is rotated in a reverse direction it will rotate freely with relation to the connecting member and the latter cannot be removed by this reverse rotation of the collar, but only by the application thereto of a suitable tool. The pawl is of a very simple character consisting merely, in the present instance, of a rectangular block of metal loosely confined in the recess in the collar and resting by gravity on the shoulder of the connecting member. Thus the pawl and ratchet connection is very inexpensive of construction and is positive in its operation.

20 While I have shown and described one embodiment of my invention I wish it to be understood that I do not desire to be limited to the details thereof as various modifications may occur to a person skilled in the art.

25 Having now fully described my invention, what I claim as new and desire to secure by Letters Patent, is:

1. In a radiator cap, a tubular member
30 having screw threads to attach the same to

the filling pipe of a radiator and having a circumferential channel, the lower wall of which has a tapered recess therein, a collar extending about said tubular member and having a rib extending into said channel to 35 rotatably connect said collar with said tubular member, said rib having an inclined slot in the inner edge thereof, a rectangular block of metal loosely confined within said slot, resting upon the lower wall of said 40 channel and adapted to enter the recess in said lower wall.

2. In a radiator cap, a tubular member having means to attach the same to the filling pipe of a radiator and having a circumferential channel, the lower wall of which has a recess therein, a collar extending about said member and having a rib extending into said channel to rotatably connect said collar with said member, said rib having a 50 recess extending transversely thereto, and a pawl comprising a block of metal loosely supported in the recess in said rib, controlled solely by gravity, and having its lower edge resting upon the lower wall of 55 the channel.

In testimony whereof, I affix my signature hereto.

HENRY J. MESCHER.
